DISPLAY RACK FOR EARRINGS

Donald C. Parke, 3605 Nelson St.,
Wheat Ridge, Colo. 80033

Filed June 11, 1968, Ser. No. 12,301

Term of patent 14 years

Int. Cl. D20—02

U.S. Cl. D80—9

—□—1

—□—2

—□—3

FIG. 1 is a top plan view of a display rack for earrings, showing my new design;

FIG. 2 is a side elevational view thereof; and

FIG. 3 is a perspective view thereof.

I claim:

The ornamental design for a display rack for earrings, as shown.
